JOSEPH EUGENE AIKEN, OF PITTSBURGH, PENNSYLVANIA, ASSIGNOR TO WESTINGHOUSE ELECTRIC & MANUFACTURING COMPANY, A CORPORATION OF PENNSYLVANIA.

MICROPHONE.

Application filed July 2, 1925. Serial No. 41,178.

My invention relates to microphones, and particularly to means therein for increasing the accuracy of translation of sound vibrations into electrical vibrations.

5 An object of my invention is to provide a microphone having a quantity of resistor granules of uniform size contained in an improved cup system.

Another object of my invention is to provide 10 a microphone in which the separation between the edge of the granule cup and the surface of the diaphragm is greater than the maximum excursion of the diaphragm and less than the radius of the resistor granules.

15 Another object of my invention is to provide a microphone structure in which damping means are provided whereby the excursion of the diaphragm is reduced and whereby a closer spacing between the edges of the 20 resistor granule cups and the median position of the diaphragm is obtained.

Another object of my invention is to provide 25 a preferential damping means whereby high vibration frequencies in the diaphragm are more effectively damped than low vibration frequencies.

Another object of my invention is to provide 30 a microphone system having a stretched diaphragm, a preferential damping means 30 cooperating therewith, a pair of resistor elements, and means for retaining the resistor granules in place without the use of unsymmetrical closures or padding.

Another object of my invention is to provide 35 a microphone having small resistor granules arranged in a symmetrical, uniform pressure system.

In the construction of microphone devices, it has been customary to embody therein a resistor element consisting of a cup filled with 40 granules, of such material as carbon or graphite, which rested against the diaphragm and were held in place by a packing of felt between the edge of the granule cup and the 45 surface of the diaphragm. This construction has been found to produce an unsymmetrical arrangement of the granules which does not give an accurate translation of the sound vibrations into electrical vibrations. The 50 failure of accuracy is probably due to random displacements in the unsymmetrical pressure system.

My invention provides means whereby the

granule mass is retained with a cup having simple surfaces only and no packing felt, 55 and whereby a simple, symmetrical distribution of the granules in the cup is obtained and a simple symmetrical pressure system provided.

The construction provided embodies damping means, which are also made to provide a preferential damping effect, comprising a pair of granule cups having simple surfaces and sharp edges, one thereof being an integral part of the damping means, and resistor granules having a radius larger than the spacing between the granule cups and the diaphragm. By this means, I am enabled to provide a microphone device in which compensation is made for the normal departure 70 of the reproduction curve from a straight line, wherein the occurrence of random departures from a straight line in individual resistors is minimized, and wherein the tendency of a microphone to respond more 75 strongly to high frequencies than to low is compensated.

Other objects and structural details of my invention will be apparent from the following description, when read in connection with 80 the accompanying drawings, wherein—

Figure 1 is a view in vertical elevation of an embodiment of my invention;

Fig. 2 is a view in rear elevation of the same; and

Fig. 3 is a sectional view along the lines III—III of Fig. 1.

The preferred embodiment of my improved microphone shown in the figures comprises a frame 1, a clamping ring 2 and a diaphragm 3 held by its edges therebetween. Clamping pressure is furnished by the screws 4.

Stretching means are provided for the diaphragm 3, comprising a ring 5 having rounded edges and a pressure ring 6 threaded into the frame 1. A back plate 7 is provided, preferably formed of insulating material, such as hard rubber. The back plate 7 is conveniently held in place by a second clamping ring 8 and is spaced away from the diaphragm by a mica ring 9.

The back plate 7 is counter-bored to form a cylindrical central recess 11, at the bottom of which is mounted a metal connector member 12 having a carbon facing 14. The con-

ductor members 12 and 14 are held in place by a threaded bolt 15 having a shoulder portion 16. The recess 11 contains a mass of granules 17 which almost fill it. Electrical connection is made to the members 12 and 14 and to the granules by a wire or other conductor attached to the binding post 18. Holes 19 are provided near the periphery of the back plate 7 for controlling the relative degree of damping of high-frequency vibrations as compared to low-frequency vibrations.

A second granule cup 21 is provided, of insulating material or having an insulating lining (not shown). Within the granule cup 21 is mounted a conducting member 22 and a carbon or graphite facing member 23. The granule cup assembly is attached to a supporting bar 24 which is held in a clamp 25. A bridge piece 26 is provided, attached to the frame 1 by screws 27 and insulated therefrom by insulating members 28 and 29. The granule cup 21 is filled with granules 31 in a manner similar to the filling of the space 11 in the back plate 7.

The granules 17 and 31 may conveniently be of a diameter between 0.010 and 0.020 inch, and may be of a single size or of several slightly different sizes.

In the assembly of the device of my invention the diaphragm 3 is placed on the frame 1, the clamping ring 2 positioned thereon and the screws 4 inserted and drawn up tightly. The pressure ring 5 is then inserted within the annular opening of the frame 1 and the ring 6 screwed down upon it with a convenient pressure, which, should be adequate to stretch the diaphragm almost to its elastic limit.

The various parts of the back plate 7 and the conductor members 12, 14, 15 and 16 are then assembled in the obvious way. A sufficient quantity of granules 17 are inserted in the recess 11 almost to fill it full. The spacing ring 9, which may be of mica, having a thickness between 0.001 and 0.002, is then laid concentrically upon the top of the back plate 7, and the frame and diaphragm assembly laid carefully upon the back plate 7.

The whole is then inverted, the clamping plate 8 positioned around the back plate 7 and the supporting screws 10 inserted and drawn up to a suitable tension.

The bridge piece 26 is then assembled with the granule cup 21, its conductors 22 and 23 and supporting member 24 and the clamp 25 in place. The complete assembly is then laid upon the frame 1 without intervening insulation and the granule cup 23 on its supporting rod 24 moved downwardly until the edges of the granule cup 23 are in contact with the diaphragm 3. The clamp 25 is next tightened to hold the rod 24 firmly in place.

The bridge member 21 may then be inverted and a sufficient number of granules 31 put

into the cup 23 to fill it almost full. The insulating pieces 28, which may desirably be mica having a thickness between 0.001 and 0.002 inch, are then laid upon the ends. The frame and diaphragm assembly are then turned over and lowered carefully upon the bridge piece. The clamping screws 27 and insulation 28 are then inserted and drawn up tightly. The construction and assembly, as indicated, provide a spacing between the granule cups and the diaphragm 3 which is less than the radius of the granules 6.

The damping action of the back plate 7 prevents the excursion of the diaphragm being greater than the spacing from the edges of the granule cups, and, therefore, there is no tendency for the granules to escape around the edges of the cup. Likewise the fact that the granule cups have no rough edges, but instead only a smooth simple surface, provides a support upon which the granules lie in a simple, symmetrical arrangement providing a simple pressure system, responsive to pressure variation, to produce resistance variations which show a characteristic curve free from random irregularities.

The diaphragm is stretched by means of the rings 5 and 6 to such a tightness that its natural period of vibration is high, preferably beyond the limit of the frequencies with which the diaphragm is intended to deal. Because the diaphragm is stretched, there is a tendency for it to respond more readily to the higher frequencies. In order to overcome this, the thin air space between the diaphragm and the back plate 7 is supplied.

When the diaphragm moves toward the back plate, the air in the central portion of this space can escape only by flowing radially until it reaches the holes 19. If the movement of the diaphragm is slow, the air has ample time to escape by flowing radially to the holes and emerging through them. If the motion of the diaphragm is rapid, the air will be compressed before it can escape and will react against the diaphragm, thereby tending to damp its movement.

When the diaphragm moves in the opposite direction, similar considerations, except that the air is rarefied instead of being compressed, apply and show that the rapid movement of the diaphragm is damped, although the slow movement is not. The action of the back plate 7, therefore, is a selective damping, the higher frequencies being damped more than the lower frequencies. The damping thereby tends to counteract the influences of the stretching and the two together produce a very uniform response.

By means of the construction embodied in my invention, I am enabled to provide a microphone device in which the gross simple departures from rectilinear translation by the resistor granules is compensated by departure in opposite directions by two resis-

tors and in which the tendency to respond differently to sounds having high or low frequencies is corrected and in which random irregularities of response by the granule systems is avoided.

5 While I have shown but a single embodiment of my invention in the preceding description, it is capable of various changes and modifications therefrom without departing from the spirit thereof, and it is desired, therefore, that only such limitations shall be imposed thereon as are required by the prior art or indicated by the appended claims.

10 I claim as my invention:

1. A microphone comprising a diaphragm, stretching means and damping means therefor, a supporting frame cooperating with both thereof, resistor cups and granules supported thereby, positioned on opposite sides of said diaphragm and spaced therefrom by a distance less than the radius of said granules.

15 2. A microphone comprising a diaphragm, stretching means and damping means causing said diaphragm to have a low excursion in response to sounds of a given intensity, resistor cups having square edges and spaced from said diaphragm a distance less than twice the excursion, and granules therein

20 having a radius greater than twice the excursion.

25 3. A microphone comprising a diaphragm, means for forming a damping chamber therefor, said means having a center recess adapted to contain resistor granules, and a second granule container on the opposite side of said diaphragm.

30 4. A microphone comprising a diaphragm, a frame therefor, and a non-conductive damping back plate having a granule recess therein, and holes therethrough adapted to control the ratio of damping of relatively high and relatively low frequencies.

35 5. In a microphone, a diaphragm, a damping means therefor comprising a plate closely adjacent to said diaphragm and having openings near its periphery only and having a recess near its center and pressure-responsive resistance material in said recess.

40 6. In a microphone, a diaphragm, a damping means therefor comprising a plate of insulating material closely adjacent to said diaphragm and having openings near its periphery only and having a recess near its center and pressure-responsive resistance material in said recess.

45 In testimony whereof, I have hereunto subscribed my name this 24th day of June, 1925.

JOSEPH EUGENE AIKEN.
